AUTOMOBILE RAIN VISOR FOR DRIVE-IN THEATRES

John P. Francis, 20 Boston St.,
Haverhill, Mass. 01830

Continuation-in-part of design application Ser. No.
19,923, Nov. 4, 1969. This application Aug. 12,
1970, Ser. No. 24,437

Term of patent 14 years

The portion of the term of the patent subsequent to
Dec. 15, 1984, has been disclaimed

Int. Cl. D12—16

U.S. Cl. D14—6

FIG.1

FIG.2

FIG.3

FIG. 4

FIG. 5

FIG. 6

FIG. 1 is a perspective view of an automobile rain visor for drive-in theatres, embodying my new design,

FIG. 2 is an extended layout view thereof,

FIG. 3 is a front elevation view of the extended form thereof,

FIG. 4 is a perspective view of a modified form of the invention,

FIG. 5 is an extended layout view thereof, and

FIG. 6 is a front elevation view of the extended form thereof.

The vehicle fragmentarily shown in broken lines in FIGS. 1 and 4 is included for illustrative purposes only.

This is a continuation-in-part of design application Ser. No. D. 19,923, filed Nov. 4, 1969, now Pat. No. D. 219,440.

I claim:

The ornamental design for an automobile rain visor for drive-in theatres, substantially as shown and described.
